ABSTRACT: A closure device for the bottom outlet opening in casting ladles is disclosed, the outlet opening having a supporting member adjacent thereto solidly connected to the casting ladle. The closure device comprises a slide plate disposed below the outlet opening and rotatable about a vertical axis. Importantly, the slide plate is hingedly mounted in such a manner that it can adjust in more than one degree of freedom to the position of the supporting member about the outlet opening. As a result thereof, the closure device can easily adjust to thermal expansions of portions of the casting ladle to maintain a reliable seal.

CLOSURE DEVICE FOR THE BOTTOM OUTLET OPENING OF A CASTING LADLE

BACKGROUND OF THE INVENTION

The instant invention generally relates closure devices and particularly concerns a closure device for the bottom outlet opening in casting ladles, such closure device being of the type comprising a slider member for opening and closing such outlet opening.

A problem presently exists in the art concerning the slider member type of the closure device in that presently known slider members cannot always reliably seal off the outlet opening of the casting ladle. Furthermore, the previously utilized devices of this type had the drawback that they either would wear out rapidly as result of the insufficiently high temperatures and forces or that they could only insufficiently adjust to the thermal expansion of portions of the casting ladle.

SUMMARY OF THE INVENTION

It is the primary object of the instant invention to provide a slider member for opening and closing the outlet opening of a casting ladle which eliminates the above-mentioned drawbacks of the prior art.

This object as well as other objects which will become more apparent as the description proceeds are implemented by the subject invention in that a slide plate is disposed below the outlet opening of a casting ladle and is rotatable about standing or vertical axis. Additionally, the slide plate is hingedly mounted in such a manner that it can adjust in more than one degree of freedom to the position of the supporting member firmly connected to the casting ladle about the outlet opening. As a result thereof, reliable sealing of the outlet opening can be obtained and the closure device is far less subject to repairs and consequent interruptions in the work process by virtue of its simplicity and strong constructions.

BRIEF DESCRIPTION OF THE DRAWINGS

The invention itself as well as other advantageous features thereof will be more clearly understood from the following detailed description of preferred inventive embodiments, such description referring to the appended sheet of drawings wherein:

FIG. 1 depicts a sectional view taken along line I-I of FIG. 2 through the bottom outlet opening of a casting ladle together with the closure device of the instant invention;

FIG. 2 depicts a sectional view taken along line II-II of FIG. 1;

FIG. 3 depicts a sectional view taken along line III-III of FIG. 1;

FIG. 4 depicts a cross-sectional view analogous to FIG. 3 taken through another embodiment of the instant invention;

FIG. 5 depicts a cross-sectional view taken through further embodiment of the instant invention utilizing a manual operation for the closure device; and

FIG. 6 depicts a cross-sectional view analogous to FIG. 2 taken through a further inventive variation.

DESCRIPTION OF PREFERRED INVENTIVE EMBODIMENTS

Referring now to the drawings, and particularly to FIG. 1 thereof, a round opening for discharging molten metal is disposed in the bottom 1 of a casting ladle 2 which serves to take up the liquid molten metal. A cylindrical insert member 3 is placed into this bottom opening, insert member 3 having a funnel-shaped portion 4 towards the top thereof and a cylindrical outlet or discharge opening 5 towards the bottom. The casting ladle 2 is provided with a jacketing sleeve 6 at the underside of its bottom portion and at its outside side wall surface. A holding ring 7 and a disc 8 disposed in the center of the holding ring are structured as parts firmly connected to the casting ladle, disc 8 having a central opening aligned with the cylindrical outlet opening 5.

A sliding plate 10 is pressed against the disc 8, sliding plate 10 having an opening 11 which can be brought selectively into a closure position or into a position which will allow it to become aligned with the opposite discharge opening 5. A frame 12 is firmly connected to the exterior of sliding plate 10 and the interior of frame 12 is covered with a refractory material 13 having a passage opening 14. Frame 12 is pivotally mounted at 13' in bushings of a lever 40 such that frame 12 is rotatable about a horizontal axis 15.

10 Lever 40 itself preferably is welded together from several parts and basically comprises a two-arm lever rotatably mounted about a vertical axis 16. The lever end furthest away from frame 12 is provided with a roller 17 which can rotate about a horizontal pivot point 30 on a roller track 18 and is able to roll on such roller track. Lever 40 is supported by a bracket 20 having side portions 21 welded to jacket 6 or otherwise firmly secured to the casting ladle. A ball pin 22 is threaded into the center of bracket 20, ball pin 22 pressing against a ball socket 23 of the lever 40. This ball socket 23 is disposed in a bushing or sleeve 24 of lever 40. A flat arm 25 is welded to the bushing or sleeve 24 as well as, on the other side of the sleeve, two braces or supports 26 which together form the lever 40. Lever 40 is bendable or flexible transversely to its plane of displacement and can be more or less bent through by means of screwing in the ball pin and thus can be pretensioned such that the sliding plate 10 can be pushed against disc 8 with sufficiently great force to effectuate reliable sealing of the discharge opening of the casting ladle. As a result of the elastic bending of lever 40, thermal expansions or distortions of the bottom of the casting ladle or other portions thereof can be accommodated without difficulty since rotatable frame 12 can adjust to each new respective position of the disc 8. In this regard, adjustment may also be obtained with respect to changes in position occurring transversely to axis 15 in that lever 40 can also yield about a horizontal axis due to the pivotal mounting of ball pin 22 in the ball socket 23. As a result thereof, sliding plate 10 can follow virtually all changes and positions of disc 8 due to thermal distortion or other reasons without the necessity of exerting an inordinately great pressure force on disc 8. Consequently, reduction of the force for displacing the sliding plate 10 is possible as compared with devices formerly used. The rotation of the lever 40 between the closure position and the opening position takes place pursuant to FIG. 2 preferably by hydraulic operated pressure means 28 having a plunger 29 hingedly connected with pivot 30 of lever 40.

Referring now to FIG. 4, a further embodiment of the instant invention is depicted. Bracket 20 in this embodiment is resiliently mounted as a result of which one can forego vertical adjustability of the ball pin. Pressure springs 31 are mounted between bracket 20 and the free ends of bolts 30'. These springs 31 can be pretensioned by means of nuts 32. Apart from this difference, the manner of operation of the device of FIG. 4 is analogous to that described with respect to the device of FIG. 1.

Instead of hydraulic displacement of lever 40 between its opening and closure position, manual displacement pursuant to FIG. 5 can also be utilized. Here, a threaded spindle 35 or toothed bar or rack is pivotally joined to the pivot portion 30 of lever 40 via a bar 34, the threaded spindle 35 being supported in a housing 36 and being displaceable with the aid of a handwheel 37.

In the variation of the inventive embodiment as depicted in FIG. 6, a one-armed flexible lever 41 is present instead of lever 40 described above. Lever 41 is supported at one end by ball pin 42 and at the other end carries a roller 38. Frame 12 is rotatably mounted by means of both pivot structures 39 and is itself constructed identically to the frame as described with respect to the embodiment of FIG. 2. Thus, it is possible in a manner similar to that described above to obtain complete adjustment of the sliding plate to counteract any deformations of the casting ladle or expansions with the device of FIG. 6.

As should now be apparent, the objects initially set forth at the outset of this specification, have now been successfully achieved.

I claim:

1. A closure device for the bottom outlet opening of casting ladles wherein a support member is firmly connected to the casting ladle about the outlet opening, said closure device comprising slide plate means disposed below said outlet opening of said casting ladle and rotatable about a vertical axis, means for hingedly mounting said slide plate means such that said slide plate means can adjust in more than one degree of freedom to the position of said support member.

2. A closure device as defined in claim 1, further including a two-armed lever means for operating said slide plate means, said lever means being attached to said slide plate means such that said slide plate means is rotatably mounted about a horizontal axis, said lever means being flexible transversely to its plane of displacement.

3. A closure device as defined in claim 2, further including a bracket attached to the casting ladle, and ball pin and ball socket means for mounting said lever means to said bracket.

4. A closure device as defined in claim 2, wherein the end of said lever means which is away from said sliding plate means

10 20

includes a roll, and roller track means attached to said casting ladle upon which said roll can travel.

5. A closure device as defined in claim 4, wherein said end of said lever means is coupled with a hydraulic pressure means for effecting displacement thereof.

6. A closure device as defined in claim 4, wherein said end of said lever means is coupled with a manual displacement means for effecting displacement thereof.

7. A closure device as defined in claim 1, further including a one-armed lever means, said sliding plate means being disposed in the central area of said one-armed lever means and being rotatable about a horizontal pivot, said one-armed lever means being resiliently supported to said casting ladle.

8. A closure device as defined in claim 3, wherein said ball pin includes thread means and is vertically adjustable in said bracket.

9. A closure device as defined in claim 3, wherein said bracket is resiliently supported by said casting ladle.
